SLIP SHEET CONTROL

Ferdinand Nigra, San Francisco, Calif., assignor
to Niagara Duplicator Co., San Francisco,
Calif.

Application January 30, 1939, Serial No. 253,495

7 Claims. (Cl. 34—1)

The invention relates to a slip-sheeting device for use at a receiving tray for printed sheets discharged from a printing apparatus, and more particularly concerns a control for the discharge of the slip sheets from a supply stack thereof and into interleaving position between the printed sheets in the tray.

An object of the invention is to provide a device for automatically and positively initiating the movement of a released slip sheet which would otherwise descend to its operative position solely by gravity.

Another object is to provide a device of the character described which is equally operative with respect to the slip sheets of a stack thereof regardless of the number of sheets in the stack.

The invention possesses other objects and features of advantage, some of which, with the foregoing, will be set forth or be apparent in the following description of a typical embodiment of the invention, and in the accompanying drawing in which,

Figure 1 is a perspective view of a slip-sheeting unit having the control device of the present invention provided in operative association therewith.

Figures 2 and 3 are fragmentary transverse sections through a slip sheet supply tray of the unit, and disclose a pressure-producing device in elevation and operative against stacks of slip sheets respectively having many and few sheets therein.

Figure 4 is a transverse section through the slip sheet supply tray and showing the pressure device inoperatively disposed with respect to a stack of slip sheets in the tray.

Figure 5 is an enlarged and fragmentary section through the pressure device.

The features of the present invention are generally applicable in connection with a slip-sheeting unit 7 for use with a printing mechanism such as a printing press or a duplicator which discharges printed sheets for gravity deposit in a tray underlying the unit, with the sheets moving laterally as they settle into place in the tray. In the present instance, printed sheets delivered from between the stencil and the impression roller of a duplicator such as that disclosed in my United States Patent No. 2,139,132 which issued on December 6, 1938, are arranged to fall into a collecting tray 8 of the unit from an end thereof, and means are provided for interposing a separator, or slip, sheets 9 between the printed sheets as the latter are delivered to the tray.

As particularly illustrated, a stack of the slip sheets 9 is arranged for support in a frame or tray 11 mounted on and above the tray 8 in unitary association therewith and having an open bottom, and means are provided for releasing the sheets 9 one at a time for falling upon a delivered printed sheet in the tray 11 before the next printed sheet is delivered, the device being known in the art as slip-sheeting.

The slip sheets 9 are alike and are each provided with two spaced notches 12 in each side edge thereof, the notches of the two sheet edges being equally spaced apart but differently spaced with respect to the same sheet end. In a stack of the slip sheets for use in the present unit, alternate sheets are reversed as to the disposal of the sheet notches 12 in the stack, whereby the correspondingly disposed notches of the sheets define four lines thereof at each stack edge defined by the side edges of the sheets. In the present slip-sheeting unit, the stack of sheets in the tray 11 is supported on four rollers 13 which engage in pairs beneath the opposite stack sides and may pass through the notches 12 when they register therewith. In plan arrangement, the support rollers 13 are spaced exactly as the notches 12 of a slip sheet 9 and are arranged for their simultaneous disposal beneath the bottom sheet of the stack at its notches 12 whereby they may engage the next higher sheet through the notches of the bottom sheet to thereby release the latter and assume the support of the stack through the new bottom sheet.

The rollers 13 are mounted on the inner ends of stub shafts 14 which extend beneath the stack from bars 15 disposed and supported at opposite sides of the tray 11 as the primary support means for the stack; in this manner, a released slip sheet 9 may fall freely into the underlying tray 8. In the drawing, the rollers 13 are shown as being disposed to supposedly engage the lower sheet of the stack. The roller-carrying bars 15 are mounted for their longitudinal reciprocation in their planes and are pivotally connected by a cross-bar 16 which is pivoted centrally of its connections with the bars 15 to a rearward projection 17 of the tray 11, the arrangement being such that a rocking of the cross-bar 16 horizontally and about its pivot point is arranged to oppositely shift the bars 15 and their rollers 13 to like degrees.

Following the release of the bottom sheet of a stack of slip sheets 9 by reason of the registration of the set of rollers 13 with its notches 12, an opposite shifting of the bars 15 to dispose

the rollers beneath the notches of the new bottom sheet will release this sheet, it thus being understood that the slip sheets 9 may be released from the bottom of the stack and one at a time by 5 oscillating the control bar 16 between limiting positions thereof which disposed the rollers 13 in sheet-releasing positions. My aforesaid United States Patent No. 2,139,132 discloses in detail one suitable means for effecting the oscillations of the bar 16 in synchronism with the delivery of printed sheets from a duplicator whereby the desired insertion of slip sheets between successive printed sheets may be effected as the printed sheets are deposited in the tray 8. 10 Since the slip sheets 9 are used repeatedly and are disposed in alternate arrangement in a stack thereof, means are preferably provided for retaining the sheets in their required order and arrangement, said means also providing a stop 15 to limit the movement of the printed sheets in the tray 8. As is particularly illustrated in Figure 1, a U-shaped member 18 is provided for the insertion of its legs 19 through spaced openings 20 provided in the sheets 9, said pair of openings defining a line transverse to the longitudinal axis of the sheets, and corresponding openings being aligned in the stack whereby the legs 19 may be disposed therethrough. The lower extremities of the legs 19 are arranged to engage in openings 21 of the bottom plate 22 of the tray 8 whereby the member 18 may be disposed and held in a plane perpendicular to that of the tray bottom to extend upwardly through 25 the slip sheet stack in which it engages. It will be understood that the legs 19 of the member 18 operate as a stop means to limit the lateral delivery movement of the printed sheets in the tray 8 for insuring their orderly disposal between adjacent slip sheets 9 as the printed sheets and slip sheets are alternately deposited in the tray. 30 It will now be noted that the slip sheets 9 comprise thin and flat pieces of cardboard or other suitable material, with or without ink-blotting faces, and are inherently stiff enough to tend to 35 retain a flat condition thereof when individually free, whereby they may have their normal flat form while falling into operative position and may be assembled for providing a compact stack having the present arrangement. The slip sheets 40 are transversely flexible while resiliently resisting bending, and a stack of such sheets supported only along its opposite sides, as by the rollers 13, has successive sheets thereof mutually engaged in 45 relatively close face-to-face relation. When the bottom slip sheet 9 of a stack is released for its falling upon a printed sheet which is being delivered beneath it, air must penetrate between the released sheet and the overlying sheet of the stack before the released slip sheet may begin 50 falling freely to its appointed place, and it has been found in practice that such air penetration may be so slow when the engaged sheets of the stack are substantially flat as to seriously limit the permitted rate of operation of the printing 55 mechanism by reason of the limitation imposed by the retarded and variable rate and direction of delivery of the slip sheets from their stack.

Experiment has shown that the foregoing air binding of the slip sheets may be largely overcome by flexing the supply stack of slip sheets 70 downwardly between the lines of support provided by the rollers 13 at its side edges, as is illustrated in Figures 2 and 3. When the stack of slip sheets is so flexed, the side edges of a released bottom sheet will positively pull away from the secured

overlying sheet by reason of the tendency of the released sheet to flatten out, the action progressively admitting air from the sheet edges and promptly freeing the sheet for its unhampered fall upon a printed sheet in the collecting tray 8. 5 It will be noted further that the straightening out of the released slip sheet will also cause it to exert a reactive kick against the overlying and bowed sheet whereby to actually start it moving downwardly at a rate faster than gravity alone would 10 produce, and so accelerate its falling.

Since uniformity in the rate and manner of the discharge and positioning of slip sheets is necessary for a most rapid and efficient operation of a printing mechanism which supplies printed 15 sheets for interleaving, means are provided for effecting a constant degree of downward flexing of the stack of slip sheets in the tray 11 independently of the number of sheets therein, whereby to utilize the benefits of bending and 20 accomplish the major objectives of the present control device, said device essentially comprising a pressure-producing assembly 24 for centrally and constantly engaging the top of the stack of slip sheets in the tray 11 to positively and constantly flex the stack to a desired degree which is determined by the resiliency of the sheets. 25

The assembly 24 essentially comprises a thrust member 25 arranged for its application transversely against the top slip sheet in the tray 11 30 more or less centrally thereof, a support element 26 mounted across the tray above the stacked sheets therein and carrying the member 25 for its guided and axial reciprocation, and a compression spring 27 constantly coactive between 35 the element 26 and the member 25 to resiliently urge a down thrust of the member against a stack of slip sheets in the tray when the member 26 is fixed in place on the tray. In the present instance, the member 26 comprises a flat and transversely rigid bar for spanning the tray and attached to a tray side 28 by means of a suitable hinge 31. A spring catch 32 is mounted at the outer face of the opposite tray side element 29 for receiving and securing the free end of the bar 40 in position adjacent and opposite the top lip of the side 29 whereby the bar may be releasably secured across the top of the tray. 45

In the present structure, the member 25 comprises a cylindrical rod and the bar 26 is centrally perforated to receive the rod 25 perpendicularly therethrough. A sleeve member 33 slidably receives the rod 25 and has one end fixed in the bar opening, said sleeve providing a guideway for the rod. A ring or flange 34 is provided on the rod 25 adjacent its sheet-engaging end and provides a spring seat between which and the opposed end of the sleeve 33 the spring 27 is constantly operative to urge the rod axially toward a limiting position which is determined by a suitable stop means. As shown, a pin 35 is mounted in the sleeve 33 to engage a slot 36 extending in a side of the rod longitudinally thereof, the slot end 36' furthest from the ring 34 engaging the pin to limit the operative extension of the rod 50 when all slip sheets have escaped from the tray 11 or the assembly 24 is inoperatively disposed. It will be understood that the extension of the pin 35 into the slot 36 also prevents a rotation 55 of the rod 25 in its mounting.

The thrust rod end which is to engage the slip sheets is forked to mount a cylindrical wheel or roller 37 which is arranged to provide an anti-friction contact end for the rod and is mounted on a pin 38 extending through the fork sides 39 70 75

in perpendicular relation to the rod axis. The plane of the roller 37 is preferably parallel to or includes the center line of the cross member 26, whereby to facilitate the swinging down of the member from the position shown in Figure 4 to forcibly and resiliently engage the rod 25 with a stack of sheets on the tray through the roller 38 as in Figure 2, it being understood that the stop pin 35 functions to maintain the aforesaid positioning of the roller for its rolling engagement across the top slip sheet as the member 26 is swung to and from its locked-down position.

The roller 38 of the operative rod 25 preferably engages the top slip sheet at or adjacent its longitudinal center line, and centrally of the sheet ends, and is arranged to constantly flex the stack of sheets downwardly along the longitudinal center line of the stack and between the pairs of support rollers 13 beneath the opposite stack sides, as is shown in Figures 2 and 3. The strength of the helical compression spring 27 is such that the desired maximum degree of bowing is produced in a full stack of slip sheets when the rod 25 is operative, and the same degree of bowing is maintained as the sheets are dropped and the spring is allowed to correspondingly expand. The latter important relation is made possible by the fact that the resistance to the bending of the stack in the disclosed manner decreases with the number of sheets therein, and it is therefore merely necessary to provide an helical spring having such a longitudinal elasticity under compression as to maintain a constant degree of bowing in the stack as the slip sheets are released therefrom and the stack becomes thinner.

With the positively operating sheet-flexing device now disclosed, the sheet-freeing action as a sheet is released will be so closely constant for all sheets of the stack that the maximum possible rate of delivery of slip sheets from a supply stack on the rollers 13 may be predetermined and maintained while using the slip-sheeting unit in association with a printing mechanism which may deliver printed sheets at said predetermined rate. Since the possible rate of delivery of the slip sheets with the present control device is constant and is appreciably greater than with a solely gravity delivery, the present device permits a much higher printing rate than would otherwise be possible. It will, of course, be understood that the weight of the thrust rod assembly which is constantly added to the push of the rod 25 comprises a minor, if not negligible, part of the flexing force against the slip sheets of a stack in the supply tray. It will also be understood that the present device is applicable to the interleaving of other than printed sheets. From the foregoing description, taken in connection with the accompanying drawing, the advantages of the present invention will be readily understood by those skilled in the art to which the invention appertains. While I have described the principles of operation, together with an arrangement which I now consider to be a preferred embodiment of my invention, I desire to have it understood that the showing is primarily illustrative, and that such changes may be made, when desired, as fall within the scope of the following claims.

I claim:

1. In a device for inserting resiliently flexible slip sheets between successively delivered sheets for separation, means supporting a supply stack of the slip sheets in generally horizontal disposi-

tion and engaging the stack solely beneath opposite side edge portions thereof, means for actuation to release the bottom slip sheet of the stack for its operative disposition by falling, and means engaging the top of the stack centrally thereof to constantly flex the same downwardly to a fixed and predetermined degree whereby the release of the bottom sheet will permit a flattening out of the released slip sheet to positively free it from the immediately overlying sheet.

2. A structure in accordance with claim 1 wherein the last means comprises a spring-pressed member which is operative transversely against the top of the stack.

3. In combination with a tray for horizontally receiving a succession of printed sheets from a printing mechanism, a device for interleaving the successive sheets during the deposit thereof comprising a structure supportedly engaging an orderly stack of resiliently flexible and inherently flat slip sheets solely beneath opposite side edges of the stack and in horizontal disposition above said tray and for the release of the successive bottom sheets of the stack to fall therefrom into interleaving position, and a pressure member constantly and resiliently reactive between said supporting structure and the top of the stack intermediate of its supported edges to flex the stack downwardly.

4. In a device for interleaving successive sheets during the gravity and like deposit thereof in a stack, a structure supportedly engaging an orderly stack of resiliently flexible slip sheets above the point of deposit of the first sheets and solely at opposite side edges of the last sheets for the release and free falling of the successive bottom slip sheets of the stack into interleaving relation with the first sheets, side elements of said structure beyond opposite sides of the stack, a rigid cross-member releasably connected to and between said side elements and spanning the stack, a thrust member extending transversely from the cross-member and engaging the top of the stack transversely and centrally thereof, and a compression spring constantly reactive between the cross-member and thrust member to forcibly engage the latter member with the stack to bow the stack downwardly between its supported sides.

5. In a device for inserting slip sheets between successive printed sheets during the gravity deposit of the latter in a stack thereof, a structure supportedly engaging an orderly stack of resiliently flexible and inherently flat slip sheets above the point of deposit of the printed sheets and solely at opposite side edges of the stack for the release and free fall of the successive bottom slip sheets of the stack thereof into interleaving relation with the printed sheets, fixed side elements of said structure at opposite sides of the stack, a transversely rigid cross-member hinged to a side element for swinging to and from a spanning disposal thereof over the stack, a catch on the other side element for releasably engaging the free end of the cross-member to secure said member in stack-spanning position in the structure, a thrust member carried by the cross-member and extending transversely thereof toward the stack and provided with an anti-friction means at its free end for engaging the top of the slip sheet stack centrally thereof when the cross-member is secured by said catch, and a compression spring constantly reactive between the cross-member and thrust member to forcibly engage the anti-friction means of the latter with

the stack to bow the stack downwardly between its supported side edges.

6. A structure in accordance with claim 5 wherein the anti-friction means comprises a roller arranged for its rotation in the plane of swinging of the cross-member.

7. In a device for inserting resiliently flexible slip sheets between successively delivered sheets for separation, means supportedly engaging a stack of the slip sheets solely at different side

edge portions thereof for supporting the stack, means for actuation to release the bottom sheet of the stack for its operative disposition by falling, and means engaging the top of the stack intermediately of the supported stack edges to constantly flex the stack downwardly to such a degree that the release of the bottom sheet will permit its flattening out to positively free it from the immediately overlying slip sheet.

FERDINAND NIGRA. 10
